UNITED STATES PATENT OFFICE.

JACOB E. NEAHR, OF NEW YORK, N. Y.

MATCH-HOLDER.

1,351,340.

Specification of Letters Patent. Patented Aug. 31, 1920.

Application filed March 4, 1918. Serial No. 220,159.

To all whom it may concern:

Be it known that I, JACOB E. NEAHR, a citizen of the United States, residing in the city, county, and State of New York, have 5 invented certain new and useful Improvements in Match-Holders, of which the following is a specification.

This invention relates to combined match-safes and igniting devices, and its object is 10 to produce an article of this character which will be compact, simple and inexpensive, and which shall afford a maximum of match-striking surface which can be readily renewed from time to time, as required.

15 This invention relates to the class of devices in which an ignition strip is employed which is wrapped around the exterior of the device. In application No. 84,009, filed March 14, 1916, the exterior strip is in the 20 form of a coil of many windings which surrounds the match-safe; a clip being provided for retaining the outer end of the strip, of which a winding is torn off as often as necessary in order to provide a fresh striking 25 surface.

It is found in practice that occasionally when the user strikes the match against said clip, the match becomes broken, which is an 30 objection; and it is one of the present objects, therefore, to avoid this liability of breaking of the matches, and also to increase to a maximum the extent of igniting surface, as well as to provide for the easy and inexpensive renewal thereof as may be required.

35 To these ends, I form the strip into a continuous band, which forms a single ply of igniting material and is slipped upon the match-safe to surround the same and offer a match-striking surface extending unbroken 40 entirely around the safe. The safe has a provision for holding on the band, and it is also provided with a cap which is a protection to the band, and also secures the same against accidentally coming off; the whole 45 presenting a simple, inexpensive, compact structure, and giving a maximum of room for the matches; the cap being removable so as to permit replacement of the worn-out band with a fresh one. The igniting material may, if desired, be made in tubular 50 form, and cut off into short lengths to form bands, which may be compactly packed for shipment.

Other features and advantages will hereinafter appear.

In the accompanying drawings,

Figure 1 is a side elevation of a combined match-safe and igniter, constructed according to the present improvements.

Fig. 2 is a detail to show the roughening 60 of the match-safe, to hold the band against creeping.

Fig. 3 is a sectional, side elevation of the device seen at Fig. 1.

Fig. 4 is a perspective view of an ignition 65 band.

Fig. 5 illustrates a tube which may be cut into lengths to form ignition bands.

Fig. 6 shows how the band may be flattened out for compact packing for shipment. 70

Fig. 7 shows the overlapping ends of the band joined by adhesive material.

Upon any suitable base 1 may be provided a pedestal 2 which may be surmounted by a safe 3, containing matches. If desired, 75 the match-safe and pedestal may be in tubular form and integral; a disk 4 being inserted in the upper part of the tube, to form a floor for the match-safe.

An annular strip or band 5 of igniting 80 material may be slipped down over the match-safe against an annular bead 6, formed thereon, as illustrated at Figs. 1 and 3.

The match-safe has provision for retaining said strip, such provision preferably consisting in making the match-safe 3 slightly tapering, or larger at its bottom than at its top, as shown, the band slipping easily down over the upper or narrow portion 3^a of the safe and coming to a tight fit upon the lower or broad portion 3^b, so that there is little or no liability of the band slipping around the safe at the match-striking operation; moreover, the safe may be provided with vertical scores 7 to roughen it, and thereby guard against creeping of the band therearound, while not obstructing the slipping of the band upon the safe. 90 95

The bands may be formed by cutting a 100 tube 8 into sections, each section forming a band. The tube may be formed in any suitable manner, and is illustrated as consisting of a wrapping of fabric, the overlapping edges 9 whereof are suitably secured by adherent material 10, Fig. 7.

To protect the ignition strip and guard against liability of accidental detachment thereof from the match-safe, there is provided a cap 11, which is of annular form and 110 has an exterior or projecting ledge 12 overhanging the strip. The cap is of about the

diameter of the match-safe, so that the capacity of the latter is not substantially diminished by reason of the use of the cap. The cap may have a tubular body portion 5 to fit tightly within the safe, so as not to be liable to accidental separation therefrom; or, if desired, the cap may have threads whereby it may be screwed into the upper end of the match-safe.

10 While the band is self-retaining upon the safe, still the invention is not limited to a self-retaining band, as other provision may be made for mechanically retaining the strip. The tapering form of the safe is preferred, because it facilitates the insertion of 15 the end of the safe within the flexible band. The band tends to expand as it is forced down, thereby giving it a tight and effective hold upon the drum. This form of the invention, therefore, is very simple to manage,

it being unnecessary to manipulate clips or catches for the strip, while the same may be readily removed and readily replaced by a new one.

Variations may be resorted to within the 25 scope of the invention, and portions of the improvements may be used without others.

Having thus described my invention, I claim:

In combination, a match-safe of slightly 30 tapering form and a band of igniting material forced upon the taper and mechanically held in position thereby against accidental movement, said match-safe having a surface roughened to prevent the band from slipping or creeping around the safe.

JACOB E. NEAHR.
